UNITED STATES PATENT OFFICE.

HENRY S. HALE, OF PHILADELPHIA, PENNSYLVANIA.

IMPROVEMENT IN CHAIRS.

Specification forming part of Letters Patent No. **146,065**, dated December 30, 1873; application filed November 21, 1873.

To all whom it may concern:

Be it known that I, HENRY S. HALE, of the city and county of Philadelphia and State of Pennsylvania, have invented an Improvement in Chairs and other Seats, of which the following is a specification:

The object of my invention is a chair having a seat or back, or both, which shall possess the qualities of cleanliness, elasticity, strength, and durability; and this object I attain by combining, with the frame of a chair, a seat, or back, or both, composed of thin elastic strips of wood united to a backing of canvas or other suitable flexible backing.

The wooden strips A are glued or otherwise cemented to and arranged closely together, but are preferably rounded at the edges, so that they may be self-accommodating with the canvas backing to the general curve of the chair seat or back to which they are applied, and so, that there shall be no sharp corners to incommod or wear the clothing of the occupant of the chair. As illustrated in Fig. 2, in the plan view, Fig. 3, and enlarged section, Fig. 4, the combined material is used as a substitute for the usual cane net-work, the seat-frame b being recessed at both front and back and sides, and a strip, d, being secured to the under side of the recessed portion, so as to form a continuous groove, a, for the reception and retention of the edges of the material, the latter fitting loosely in the said groove, which thus simply confines it without detracting from its elasticity.

I propose, in some instances, to re-enforce and strengthen the combined material by a strip or strips, e, of fabric or thin steel, extending beneath the same, and secured to the op-

posite sides of the seat-frame, as shown in the enlarged sectional view, Fig. 5.

In applying the material to the backs of chairs, I intend, in some cases, to adopt the same plan as that described in connection with the seat, and in other instances to adapt the ends only of the strips A to grooves in the frame.

The enlarged sectional view, Fig. 6, illustrates another method of securing the material to a chair-seat, the interior of the latter, which is supposed to be circular in the present instance, being recessed to form a shoulder, f, upon which rests a thick strip of rubber, h. The rubber sustains and imparts additional elasticity to the material, which is secured by extending a portion of the canvas behind the rubber, and fastening the whole by nails i.

The combined material, being flexible, is especially applicable to the backs and seats of folding chairs, and to camp chairs or stools, as shown in Fig. 7. It may also be used for settees, and for the seats of street-cars, &c.

An ornamental appearance may be imparted to the material by securing strips of light and dark woods alternately to the canvas backing.

I claim as my invention—

A chair with the frame of which is combined a seat or back, or both, consisting of wooden strips united to a canvas backing, all as set forth.

In testimony whereof I have signed my name to this specification in the presence of two subscribing witnesses.

HENRY S. HALE.
